UNITED STATES PATENT OFFICE.

HENRY D. STARR, OF TEXANA, TEXAS.

IMPROVEMENT IN COTTON-BALE TIES.

Specification forming part of Letters Patent No. 142,527, dated September 2, 1873; application filed July 26, 1873.

To all whom it may concern:

Be it known that I, HENRY D. STARR, of Texana, in the county of Jackson and State of Texas, have invented a new and valuable Improvement in Cotton-Bale Tie; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a sectional view of a cotton-bale with my tie attached. Fig. 2 is a top view of my cotton-bale tie. Fig. 3 is a sectional, and Fig. 4 a detail, view of the same.

This invention has relation to tie-plates for cotton-bales; and it consists in the construction and novel arrangement of a pair of slotted and hooked plates, having the same form and adapted to engage with each other in such a manner as to form a double lock, with one of the tongues or hooks bent under the catch-bar of the opposite plate between said plate and the bale.

In the accompanying drawings, the letter A designates the bale, whether of cotton, hay, or other substance. B indicates the iron strap, passing around the bale and having its ends passed through the slots of the tie plates, and bent backward under the rear bar *a* of each plate. The ends are thus arranged to be pressed between said bars and the substance of the bale. C C indicate the tie-plates, similar to each other in form, and provided each with a slot, *b*, and a tongue, *c*, the slot *b*, in each case, being sufficiently broad for the reception of the tongue or hook *c* of the opposite plate. Each plate is constructed with a transverse catch-bar, *d*, from the middle portion of which the hook *c* projects, a transverse strap-bar, *e*, opposite said catch-bar, and two side bars, *g*, connecting the catch-bar with the

strap-bar. On the same side of each side bar, with the hook *c*, is preferably arranged a projection, corrugation, or stop, *v*, at a suitable distance from the end of the plate to prevent the catch-bar of the opposite plate, when in position, from slipping backward out of engagement. The hook or tongue *c* is bent backward parallel with the catch-bar, and at a distance therefrom about equal to the thickness thereof.

The strap having been secured to the strap-bar by bending its ends through the plate-slot and under said bar, as above described, the plates, being reversed in position with reference to each other, are brought together and interlocked, the tongue of each engaging with the catch-bar of the opposite plate. In this manner a double lock is formed, either tongue being sufficient to hold the strap in case of fracture of the other. The under tongue being pressed against the bale is scarcely liable to displacement or accidental fracture, and is very secure. Sometimes the tongue may be formed on the inside edge of the catch-bar, saving material.

What I claim as new, and desire to secure by Letters Patent, is—

A pair of tie-plates, each consisting of a catch-bar, *d*, and a strap-bar, *e*, connected at their ends by side bars *g* surrounding a slot, *b*, and having extending from the catch-bar, on opposite sides, a tongue or hook, *c*, adapted to engage with the catch-bar of the opposite plate, forming a double lock, as shown and described.

In testimony that I claim the above I have hereunto subscribed my name in the presence of two witnesses.

HENRY DANIEL STARR.
